UNITED STATES PATENT OFFICE.

EGBERT H. CASTLE, OF QUINCY, ILLINOIS.

COMBINATION COOKING-STOVE.

1,214,424.

Specification of Letters Patent. Patented Jan. 30, 1917.

Application filed September 11, 1916. Serial No. 119,516.

To all whom it may concern:

Be it known that I, EGBERT H. CASTLE, a citizen of the United States, residing at Quincy, in the county of Adams and State 5 of Illinois, have invented new and useful Improvements in Combination Cooking-Stoves, of which the following is a specification.

My present invention pertains to cooking 10 stoves or ranges of the combined coal and gas type, and it contemplates the provision of a construction and relative arrangement of parts calculated to effectually prevent the appurtenances employed when gas is used 15 as a fuel from interfering with the efficiency of the heat values afforded by the combustion of coal, wood and the like when the latter are used as fuel, and vice versa.

The invention also contemplates the provision 20 of a construction which renders it feasible to employ coal or wood and gas as fuel at one and the same time, as when it is desired to highly heat the oven.

Other advantageous characteristics of the 25 invention will be fully understood from the following description and claims when the same are read in connection with the drawings, accompanying and forming part of this specification, in which:

Figure 1 is a perspective, partly broken away, and showing a combination cooking stove constructed in accordance with my invention. Fig. 2 is a detail transverse section, taken in the plane indicated by the 35 line 2—2 of Fig. 1, and showing the conduits for the products of combustion from the gas burner complementary to the oven.

Similar numerals of reference designate 40 corresponding parts in both views of the drawings.

In furtherance of my invention, the body 1 may be of the ordinary construction common to cooking stoves and ranges, and may be provided in its top with a plurality of 45 openings normally closed by lids 2, and may also be provided at its top with a plurality of gas burners 3, designed to be supplied through a manifold 4 that is adapted to be connected with a source of gas supply. The 50 arrangement at the top of the body 1 is not, however, of the essence of my invention, and therefore the burners 3 may be omitted or employed in the discretion of the manufacturer of the stove. It is also to be understood 55 that the body 1 is provided with the usual fire-box to receive coal, wood and

analogous fuel and with the usual flue space in communication with the fire-box and designed to be connected in the ordinary or any other approved manner with an uptake. 60 It is further to be understood that the oven may be and preferably is connected with the flue space in the ordinary well-known manner.

As clearly shown in Fig. 1 the oven is provided with a bottom wall 12 and end walls 11, and in the latter are apertures 10 and 10^a, respectively. It will also be noticed that the oven wall 11 adjacent to the fire-box 15 of the stove is separated from said fire-box by an intervening space 13, and that said space 13 is in communication with a chamber 14 which is provided in its bottom wall with apertures 6 for the admission of atmospheric air in sufficient volume to adequately support combustion.

Arranged in the chamber 14 and extending transversely of the stove is an apertured gas burner 5 which is designed to be supplied with gas from a suitable source of 80 supply through a valved conduit 7.

Connected to and spaced apart on the bottom wall 12 of the oven are conduits 8, the upper portions of which are formed by the said oven wall 12 so as to enable the 85 flames and heated products of gas combustion in the conduits to act directly against the wall 12 in the heating of said wall and the oven. The mouths of the said conduits 8 are in communication with the chamber 90 14 as illustrated, so as to receive the flames and heated products of combustion from the burner 5, and the ends of the conduits 8 remote from the chamber 14 are merged into upstanding conduits or conduit portions 95 95 which are arranged against and connected to the adjacent oven wall 11 and are also arranged in communication with the apertures 10^a in said wall so as to discharge the heated products of combustion into the portion of the oven remote from the chamber 14.

It will be readily appreciated from the foregoing that by virtue of the conduits 8 being spaced apart across the bottom plate 12 of the oven, the heat and products of combustion from a coal or wood fire are enabled to directly contact with the said plate 12 and are also enabled to heat the air in the conduits which affords a high heating of the oven. It will also be noted that the conduits 8 effectually prevent the smoke, soot and foul 105 110 gases from a coal or wood fire from coming

in contact with the gas burner 5 or with the atmospheric air that circulates through the conduits 8. It will further be appreciated that a portion of the products of combustion from the chamber 14 passes through the space 13 and the apertures 10 into the oven and in that way equalizes the heat in the oven when gas is employed as the fuel.

Incidental to the use of my novel combination stove it will be noted that either gas or coal or analogous fuel may be employed without any change in the construction and without any adjustment of parts; also, that when deemed desirable coal, wood or the like, may be burned in the fire-box 15 and gas may be burned in the chamber 14 at one and the same time, though this is ordinarily not preferable. It will also be noted that in the use of my improvement I am enabled to heat a gas oven with coal while keeping the coal from coming in contact with the gas by the conduits 8, which renders the oven effective and economical for either coal or gas.

Having described my invention what I claim and desire to secure by Letters-Patent, is:

1. A combination coal and gas cooking stove, comprising a body, a fire-box and an oven in said body; said fire-box and oven being separated by an intervening space in communication with the interior of the oven, a chamber arranged below and in communication with said intervening space, a gas burner in said chamber, and longitudinal conduits spaced apart on the underside of the bottom plate of the oven and formed in

part by said plate and communicating at their inner ends with said chamber and having upstanding portions at their outer ends formed in part by the adjacent oven plate 40 and communicating through apertures in said plate with the portion of the oven remote from the burner chamber.

2. In a cooking stove, a body, an oven therein, a burner chamber arranged below the oven at one end thereof, a burner in said chamber, and longitudinal conduits spaced apart on the underside of the bottom plate of the oven and formed in part by said plate and communicating at their inner ends with the burner chamber and having upstanding portions at their outer ends formed in part by the adjacent oven plate and communicating through apertures in said plate with the portion of the oven remote from the burner 50 chamber.

3. In a cooking stove, a body, an oven therein, a burner chamber arranged below the oven at one end thereof, a burner in said chamber, and longitudinal conduits spaced apart on the underside of the bottom plate of the oven and formed in part by said plate and communicating at their inner ends with the burner chamber and at their outer ends with the interior of the oven.

In testimony whereof I have hereunto set my hand in presence of two subscribing witnesses.

EGBERT H. CASTLE.
